(57) **CLAIM**

The ornamental design for an eyeglass retainer, as shown and described.

DESCRIPTION

FIG. 1 is a perspective view of an eyeglass retainer according to my new design.

The eyeglass retainer is shown in association with a pair of eyeglasses, in a first installed condition. The pair of eyeglasses, shown in broken lines, does not form part of the claimed design;

FIG. 2 is a perspective view of the eyeglasses retainer of FIG. 1, with the eyeglass retainer being shown in a second installed condition with respect to the pair of eyeglasses; FIG. 3 is a perspective view of the eyeglass retainer of FIG. 1, with the eyeglass retainer being shown in a third installed condition with respect to the pair of eyeglasses;

FIG. 4 is a top plan view of the eyeglass retainer of FIG. 1, the bottom plan view being a mirror image thereof;

FIG. 5 is a right side view of the eyeglass retainer of FIG. 1, the left side view being a mirror image thereof; FIG. 6 is a front view of the eyeglass retainer of FIG. 1; and, FIG. 7 is a rear view of the eyeglass retainer of FIG. 1.

The broken line representation of the pair of eyeglasses in FIGS. 1-3 represents environmental structure and is for illustrative purposes only. The broken line representation forms no part of the claimed design.
